UNITED STATES PATENT OFFICE.

MEIER GEO. HILPERT, OF HARRISBURG, PENNSYLVANIA, ASSIGNOR TO BETHLEHEM STEEL BRIDGE CORPORATION, OF BETHLEHEM, PENNSYLVANIA, A CORPORATION OF DELAWARE.

SINGLE TURN-TABLE CONSTRUCTION.

1,324,820.

Specification of Letters Patent. Patented Dec. 16, 1919.

Application filed April 29, 1918. Serial No. 231,443.

To all whom it may concern:

Be it known that I, MEIER GEO. HILPERT, a citizen of the United States, residing at Harrisburg, in the county of Dauphin and 5 State of Pennsylvania, have invented certain new and useful Improvements in Single Turn-Table Construction, of which the following is a specification.

This invention relates to turntables which 10 are particularly adapted and designed to reverse locomotives or other rolling stock or place the same on another track alinement, and has particular reference to a turntable construction of the multiple span type.

15 To this end the invention contemplates a turntable of the two-span tandem type which involves a simple and practical construction having a minimum number of parts which not only renders the entire structure more 20 economical to build, but at the same time permits of utilizing structural members which give a maximum strength whereby all loads from both spans may be effectually centralized to allow of an even load distribution over any desired type of center bearing. In this latter connection it is proposed to utilize a single central cross girder construction which may be supported on a 25 suitable center or pivot to concentrate all 30 of the variable loads and shocks from either or both spans on the center.

A further object of the invention is to provide a single central cross girder which not only has the advantage of being lighter 35 than the usual two cross girders, but which permits of greater security in attaching the adjacent ends of the spans, which is an especially desirable feature because preserving continuity of track under the constant 40 shocks of running heavy locomotives and rolling stock on and off of the turntables. That is to say, a single cross girder of the type proposed by the present invention gives greater stability for both spans, al- 45 though permitting of a slight flexing of the latter at or near the center to better take care of the varying loads as will hereinafter more fully appear.

A further object of the invention is to 50 provide a single cross girder construction which permits of the slight flexing of the spans above referred to in a thorough and practical manner and under all conditions of use such as the variability of tracks on 55 opposite sides of the pit, settlement of

tracks and any slight unevenness of center foundation. In this connection the flexing point of the cross girder must be capable of taking care of loads and stresses of the spans which it connects, while at the same 60 time stabilize the load, and to this end it may be observed that the flexing point should be placed as nearly as may be at the middle depth of the span girders so as to reduce the movement of either top or bottom 65 edges to thus preserve the continuity and surface of the turntable track.

A still further object of the invention is to provide a novel lateral system which is particularly adapted to the tandem type of 70 turntable span construction involving a single cross girder as previously set forth, whereby the thrusts and stresses placed upon the table may be readily taken care of. That is, the invention also proposes to pro- 75 vide in combination with the single cross girder and flexing connection, a lateral system which while allowing the transverse flexing of the cross girder on the center bearing to evenly distribute the turntable 80 loads on said center, and while also allowing the ends to adjust themselves to the several supporting trucks, is also nevertheless rigid and strong against all other forces and meets all of the requirements due to 85 heavier rolling stock and greater power which is utilized to turn the table more rapidly than has heretofore been the case.

Furthermore, to render the lateral sys- 90 tem more effective, in combination with the single cross girder construction, it is pro- 95 posed to arrange the same through the turntable in such a manner that it will pass through the center of flexure, that is, through the point of no flexure. Thus, since the lateral system is intended to take care of the power and braking thrusts laterally in the direction throughout the length thereof, it should be as direct as possible, and hence extends preferably from point 100 of power application to and through the point of no flexure. This is thoroughly provided for by the novel arrangement referred to.

With the above and other objects in view 10 which will more readily appear as the description of the invention progresses, the latter consists in the novel combination, and arrangement of parts hereinafter set forth and claimed,

Preferred and practical embodiments of the present invention are illustrated in the accompanying drawings, in which:—

Figure 1 is a vertical sectional view of a 5 turntable of the tandem span type including a single cross girder constructed in accordance with the present invention, and also showing the lateral system extending from the point of power application to and 10 through the point of no flexure.

Fig. 2 is an enlarged top plan view of the construction shown in Fig. 1 illustrating in slightly larger form the construction of one 15 span and the cross girder, and also the lateral system.

Fig. 3 is a vertical cross sectional view taken at the center of the turntable and showing the turntable center and single cross girder in elevation.

20 Fig. 4 is a vertical sectional view taken at the intermediate portion of one of the spans showing how the intermediate vertical cross bracing means only extends part of the depth of the girders comprising the 25 span, *i. e.* from the top of the girders down to the plane of the lateral system.

Fig. 5 is a vertical cross section taken at the truck end of the span.

Fig. 6 is an enlarged detail horizontal section 30 showing one form of cross girder construction and a portion of the lateral system.

Fig. 7 is a vertical sectional view showing the cross girder construction of Fig. 6 35 in elevation.

Fig. 8 is a horizontal sectional view showing a further modified form of cross girder.

Fig. 9 is a view similar to Fig. 8 showing a still further modified type of cross 40 girder and a special bolt device for carrying the lateral system past the cross girder on the outside of the girders of the adjoining spans.

Fig. 10 is a vertical sectional view taken 45 longitudinally of the turntable showing how the lateral system may be placed along the plane of the top flanges of the girders of each span, and may be thence drawn down at the ends to the point of no flexure.

50 Fig. 11 is a detail elevation of a cast cross girder.

Fig. 12 is a detail top plan view of a cross girder involving a special form of flexing pivot.

55 Fig. 13 is a detail side elevation of the construction shown in Fig. 12.

Similar reference characters designate corresponding parts throughout the several figures of the drawings.

60 In carrying the present invention into effect, it will be observed from Fig. 1 of the drawings that it is proposed to provide a divided or tandem span turntable which essentially consists of the separate span sections A—A each of which consist of the vertical

girder elements B—B, and are connected at their inner end portions by means of a novel cross girder construction designated generally as C, which latter includes a flexible joint or hinge of a suitable character which is located adjacent or within the vertical plane of the cross girder, and also the turntable center D which latter supports and carries the entire turntable and its superposed load. This type of turntable, includ- 75 ing the spans A—A, supports the turntable track in the usual way, and each section of the divided span which includes the girders B—B is provided with a lateral bracing system designated generally as E which 80 gives the girder sufficient strength transversely to take the transverse and longitudinal thrusts of the span loads and carry the same to the point of no flexure which is the pivoting plane.

Referring now more particularly to the divided span construction it may be noted that the girders B—B of each span are preferably of the I-beam type and may be built up structurally by web plates and angle 90 irons to produce the usual web for the beam and the top and bottom flanges thereof. That is to say, each of the girders B may consist of the central vertical web plate 1 having secured thereto the top angle irons 2 and bottom angle irons 3 as clearly shown in Figs. 3 to 5 inclusive of the drawings while the intermediate portions of the upper and lower surfaces of the top and bottom flanges thus formed may be provided with 95 suitable reinforcing plates 4. The said vertical webs 1 of the girders also preferably have on their inner and outer faces at suitable spaced intervals a plurality of vertical stiffening bars 5, while the truck end of each girder is made of considerable less depth than the body thereof and is provided with suitable transverse bracing webs 6 as clearly shown in Fig. 5 of the drawings. This construction of the girders B provides 100 a relatively deep girder section from its inner end to a point adjacent its truck end, at which point the said girders are made shallower, or in other words are under cut to provide clearance for the bed of the track T on which the wheels W of the turntable trucks travel. Thus, where the greater 110 strength is required the girder of each span is of greater depth and is therefore better capable of withstanding the stress of the 115 load imposed thereon, which as is well known, is of varying magnitude and relatively great moment.

The inner sides of the girders B are connected by the transverse brace elements 7 125 arranged at suitable intervals and each preferably consists, as shown, of the top and bottom angle members 8 and 9 whose vertical flanges have securely fastened thereto the end tie plates 10—10, 11—11 and the 130

- intermediate plates 12-12, which plates are connected by the crossed angle braces 13-13, 14-14. This arrangement provides a strong and rigid union for the webs of the 5 opposite girders B-B, and as shown the same extends from the top of the girder down to the horizontal plane of the lateral bracing system E, and forms a part of this system.
- 10 The foregoing structural details of the girder construction of the separate spans may be varied according to requirements without in any way departing from or affecting the salient features of the invention. One of these salient features is, as heretofore indicated, that of providing a two-span turntable with a flexing joint or hinge possessing the capacity of permitting a slight vertical flexing of the inner ends of 15 the separate span sections, while at the same time being sufficiently strong and rigid to resist and sustain loading thrusts in all other directions. Various forms of construction may be employed to provide a flexing joint or hinge capable of performing these functions, and this joint or hinge may be combined with the lateral system in any practical manner, but one preferred and practical embodiment is illustrated in Fig. 20 30 35 40 45 50 55 60 65 70 75 80 85 90 95 100 105 110 115 120 125 130 of the drawings. Likewise various types of single cross girder constructions may be employed, but in each case it is proposed to employ such a construction as will provide a hinging or flexing point for the opposite span sections of the turntable. Accordingly, reference will now be made to certain of the preferred and practical types of cross girder constructions for accomplishing the ends referred to.
- 40 In the form of construction illustrated in Figs. 6 and 7 of the drawings the flexing joint or hinge is consolidated with elements of both the span and single cross girder, and with particular reference to this consolidated structure, it will be first observed that opposite faces of each of the girders B have secured thereto the vertically disposed sets of angle irons 15-15 and 16-16, which angle irons are intended to connect the spans with the central cross girder C in such a manner that each span will be rigidly and securely connected longitudinally and laterally, but at the same time adapted to flex vertically under the varying condition 55 of load to properly and evenly distribute and concentrate the entire load of the connected spans onto the turntable center D which is located below the plane of the lower-most flanges of the girder and also the bottom 60 of the cross girder as clearly shown in Figs. 1 and 3 of the drawings. The single cross girder unit, shown in these figures of the drawings, consists of a pair of duplicate cast frames designated generally as F which 65 may be so arranged as to provide a clearance

17 at their inner ends to accommodate an electric conduit or cable post 18. These cast frames F, are as shown in dotted lines in Fig. 7, of rectangular form and include the upper and lower horizontal attaching bars 19 and 20 and the intermediate bolting web 21, while the inner member 22 thereof constitutes a vertical bolting part and the outer member 23 thereof is of relatively greater width and of special construction forming 75 a coupling and hinging web for the opposite aligned girders of the separate turntable spans. That is to say, the outer member 23 of the cast frame F is adapted to have secured thereto by a plurality of bolts, rivets or equivalent fastenings 24 the vertical terminal angle members 15-15 or 16-16, as the case may be, of the adjoining girders of the turntable, while the portion of the frame 23 between the vertical bolting areas 80 is cut away or recessed on both sides as indicated at 25 in Fig. 6 of the drawings, except for a point somewhat below the middle thereof as at 26 which latter remains in the plane of the bolting surfaces of the opposite 85 faces of the frame to thereby provide in effect a rigid pintle element about which the relative flexing movement of the vertical webs 1 of the girders may take place. The location of this horizontal pintle point 26 is at the point of no flexure, or the point where the effect of the superposed load 90 exerts no strain or stress in either one direction or the other from a perpendicular plane. The flanges of the angle member 15-15 or 16-16 are of course secured to the fulcrum or pintle member 26 by means of the extra fastening elements 27, thus rigidly anchoring the beams or girders at 95 their points of no flexure to the cross girder. 100 105 110 115 120 125 130 It will of course be understood that each girder B of the span is similarly attached to one of the cast frames F, and in order to rigidly unite and connect the said frames to provide in effect a solid single cross girder, the said frames have riveted or otherwise secured to the opposite faces thereof, by means of the fastenings 28, the cross girder web plates 29 and 30. These plates have secured to their outer faces the upper and lower horizontally disposed stiffening angles 31 and 32 and the intermediate 115 120 125 130 135 140 145 150 155 160 165 170 175 180 185 40 which may be rigidly secured to the said angles 33 and 34 by means of the fastenings 41, and projects beyond the edges of the horizontal members of said angle elements 5 33 and 34 whereby the brace elements of the lateral system E may be rigidly secured thereto by the fastenings 42 or their equivalent. All of these points of attachment are located within the horizontal plane termed 10 herein the plane or point of no flexure which includes the pintle points 26.

To further assist in bracing and stabilizing the central cross girder, the intermediate portion thereof may be provided on opposite 15 sides thereof as shown in Figs. 6 and 7 with the reversely disposed and vertically arranged angle members 43 which are in two sections, respectively arranged above and below the reinforcing elements 33 and 34. 20 Thus, it will be apparent that a strong and rigid single cross girder is provided by the form of construction shown in Figs. 6 and 7 of the drawings which not only provides a flexing point for the opposite girders of 25 each span, but also provides a central cable post clearance for accommodating the conduit or cable post that supplies electrical energy to the power units which drive the turntable.

30 In the structure described it will be apparent that a rigid union horizontally is effected between the adjoining girders of the separate span sections, at the pintle point 26. Hence above and below these pintle points 35 the unattached portions of the terminal girder angles 15 and 16 will necessarily yield or flex sufficiently to allow for the slight flexing or hinge-like action between the connected ends of the span girders 40 when the load is imposed thereon, thus permitting the proper and equal distribution of the load onto the pivoting center through the cross girder. It will be also observed that the lateral system primarily consisting 45 of the diagonal bracing between the span girders has a direct and rigid connection with cross girder within the plane of no flexure. And, in order to preserve the continuity of the lateral system and maintain 50 its bracing effect longitudinally throughout the entire turntable, the brace elements 36 are utilized as the inside tie members between the two spans for the lateral system, and separate outside tie members 44 are provided. These outside tie members 44 consist of one or more horizontal web plates arranged longitudinally of the structure, and span or bridge the joint between the span girders on the outside of the latter. At 55 their ends these outside tie members 44 are suitably fastened as at 44^a to the span girders, and at an intermediate point, as at 44^b are wedged between the stationary lugs 44^c projecting outwardly from the edges of 60 the frame 23.

Beyond the connection of the lateral system with the cross girder, the said system may extend in the same horizontal plane throughout the span sections as shown in Fig. 1, or as suggested in Fig. 10 may be 70 deflected so as to lie substantially in the plane of the top or compression chords of the girders, or if desired or required may be dropped to lie substantially in the plane of the bottom or tension chords of the girder, 75 or both. In all cases however, the lateral system connects with the central cross girder in the plane of no flexure, and will effectively act as a stay for the center of the cross girder opposite the line of no flexure, thus 80 giving the cross girder ample capacity for taking and resisting the longitudinal thrusts of the span loads.

Such modified structures as shown in Fig. 8 of the drawings would obviously carry out 85 all of the features and functions of the invention, and as will be observed from said figure a modified form of cross girder is shown, the same consisting of a pair of web plates 45 which are drawn flatly together at 90 both ends while their intermediate portions are bowed and held apart by a plurality of filler elements 46 to provide a clearance for the cable post 47, while auxiliary fillers or spacing elements 48 may also be utilized. 95 The opposite end portions of the webs 45 which are drawn together are adapted to have the ends of the girders B secured thereto with angles 15 and 16 in substantially the same manner as in the preceding 100 described form of cross girder, and in order to provide the necessary clearance for accommodating the flexing of the opposite girders, the opposite sides of the webs 45 are provided with the spaced vertical filler members 49 while at the point of no flexure there is provided a transverse pintle element 50 shown in elevation in Fig. 8. The angle members 15—15 and 16—16 are connected to the filler members 49 and 50 which together 110 are substantially H-shaped to provide a rigid connection between the spans and the cross girder. In this type of girder it is also proposed to utilize suitable horizontal stiffening angles 51 which co-operate with the 115 oblique bracing plates 52 to constitute the inside ties of the lateral system and brace the webs 1 of the girders against oblique strains, while at the same time vertical stiffening angles 53 may be utilized to perform the additional strengthening function for the central portion of the web plates 45. The lateral system E may also be secured by fastenings 54 to the anchor plates 55 arranged on opposite sides of the cross girder and located in the plane of no flexure thereof, and the outside ties 44^x for bridging the joint may be the same as those shown in Figs. 6 and 7.

A still further modified form of built up 130

cross girder is shown in Fig. 9 of the drawings wherein a pair of relatively heavy single webs 56 are utilized, the same being spaced a sufficient distance at their inner 5 ends to provide a clearance for the cable post 57 while their outer ends are provided with the vertical fillers or spacing elements 59—59 and also the transverse pintle element 60 located at the point of no flexure, to 10 thus provide the same type of hinge connection for the terminal angle members 15—15 and 16—16 of the girder elements as is provided in the other forms of the invention. The modified form of cross girder 15 shown in Fig. 9 illustrates another way of continuing the lateral system through the point of no flexure on the outside of the girders B by means of the bolts 61 having the usual heads 62 and the usual nuts 64, 20 and which pass through the angle members 15—15 and 16—16 rigidly carried by the opposite girder elements B—B. Obviously, when the nut 64 is tightened up on the bolt 61 the opposite span girders will be rigidly 25 connected at the point of no flexure in the same manner as the built up outside tie member 44 connects the opposite span girders in the other forms of the invention. To assist the outside tie bolt 61 of the lateral system 30 in maintaining the desired rigidity at the point of no flexure, it is proposed to also employ the obliquely disposed inside tie members 65 which connect with the transverse angle plates 66 bolted to opposite faces 35 of the separate webs 66—66. In this form of the invention it will also be observed that in order to produce the desired vertical stiffness and necessary reinforcement of the cross girder vertical angles 67 are also employed, 40 as are likewise the anchor plates 68 located in the plane of no flexure of the cross girder and adapted to have secured thereto by fastenings 69 or other equivalent the obliquely disposed brace elements of the lateral system E. 45

A still further modified form of cross girder is suggested in Fig. 11 of the drawings. This cross girder is made of a single casting, whereby absolute solidity and rigidity thereof is insured, and as will be observed from the drawings all of the important features and characteristics of the cross girders heretofore described are preserved. That is to say, this cast type of cross girder 50 includes the opposite coupling end portions 70 which are provided with the vertical bolting faces 71 and horizontal pintle elements 72 while projecting from their outer edges are the spaced lugs 73 which provide the necessary clearance for the outside members of the lateral system. The web portion 74 of the cross girder is provided with a horizontally extending anchor portion 75 located within the plane of no flexure for the 55 purpose of receiving the ends of the lateral

system, and the extreme lower edge thereof is provided with a saddle base 76 for the upper shoe of the load distributing unit.

As further illustrating the range of modifications comprised within the scope of the present invention, reference may be made to Figs. 12 and 13 of the drawings which show a special type of hinge located adjacent to the cross girder and adapted to permit of a relatively greater degree of flexing between 75 the span sections. As will be observed from these figures the vertical web 1^a of one of the span girders is carried beyond the plane of the web of the cross girder C and has fitted to opposite sides thereof the hinge 80 plates 77 whose spaced outer ends 78 provide ample clearance for the tenon end 79 of the vertical web 1^b of the opposite cross girder. The said spaced ends 78 of the hinge plates 77 and the tenon end 79 are provided with 85 suitable registering openings 80 in the plane of the point of no flexure for receiving a relatively stout pivot pin 81 which may be held against axial displacement by means of a key 82 or its equivalent. It will of 90 course be understood that the lateral system E is also employed in connection with this type of hinged joint, the inner end of the same connecting as at E' with the anchor plate E² located in the plane of no flexure 95 on the cross girder.

From the foregoing it will be apparent that according to the invention the idea of a turntable including opposite span sections flexibly connected, in combination with a 100 lateral system having a rigid connection with the cross girder at a point in the plane of the point of no flexure is preserved in all forms of the invention, and it will of course be understood that various changes in the 105 form, proportion and minor details of construction in the turntable proper may be resorted to and still come within the scope of the foregoing cardinal features of the invention.

I claim:—

1. A turntable construction including opposite span sections flexibly connected, and a lateral system having a rigid connection through the line of no flexure. 110

2. A turntable construction including separate span sections, a central cross girder, and a lateral system having a rigid connection with the cross girder through the line of no flexure. 115

3. A turntable construction including separate span sections flexibly connected, a single cross girder centrally located, and a lateral system having a rigid connection with the cross girder through the line of 120 no flexure.

4. A turntable construction including separate span sections, and each having a pair of spaced girders, a single cross girder connecting the opposite span girders ad-

- jacent the flexing point, and a lateral system having a rigid connection with the cross girder through the line of no flexure.
5. A turntable construction including 5 separate span sections, a single cross girder connecting opposite span girders adjacent the flexing point and provided with intermediate anchoring plates, and a lateral system rigidly connecting with said plates.
- 10 6. A turntable construction including separate span sections, a single cross girder connecting opposite span girders adjacent the flexing point and provided with intermediate projecting anchoring plates lying 15 within the plane of no flexure, and a lateral system rigidly connected with said plates.
7. A turntable construction including opposite span sections, and a cross girder having connections with the adjoining span sections forming flexing joints therefor.
- 20 8. A turntable construction including opposite span sections, and a single cross girder having connections with the adjoining span sections forming flexing joints therefor.
- 25 9. A turntable construction including opposite span sections, and a cross girder having connections with the adjacent span sections forming flexing joints therefor, and a lateral system connecting with the cross 30 girder through the plane of no flexure.
10. A turntable construction including separate span sections, a cross girder having a jointed connection with the end of the span sections forming flexing points therefor, and a lateral system connecting with the cross girder through the plane of no flexure and including horizontal rigid tie members rigidly connecting with both span sections and bridging the joints.
- 35 11. A turntable construction including separate span sections, a cross girder having a jointed connection with the ends of the span sections forming flexing points therefor, and a lateral system connecting 40 with the cross girder through the point of no flexure, and including horizontal outside rigid tie members rigidly connecting with both span sections and bridging the points.
- 45 12. A turntable construction including 50 separate span sections, a cross girder having a jointed connection with the ends of the span sections forming flexing points thereof, and a lateral system connecting with the cross girder through the point of no flexure, 55 and including horizontal outside and inside rigid tie members rigidly connecting with both span sections and bridging the points.
13. A turntable construction including 60 separate span sections having girders and a flexing joint comprising opposite and flexing flanges on adjoining girders, and a rigid coupling member clamped between said opposite flanges and having a rigid pintle element.
- 65 14. A turntable construction including opposite span sections consisting of relatively deep girder elements, a single cross girder connecting the inner end of said span sections, and a center bearing for rotatably supporting the entire turntable, said center bearing being disposed entirely between the plane of the girders of the span sections and connected to the cross girder. 70
15. A turntable construction including opposite span sections consisting of relatively deep parallel girder elements, a lateral system connecting the same, a single cross girder having its opposite side portions formed to provide a flexing clearance, and means for connecting the inner end of each 75 span section to the cross girder to permit of the relative flexing of said span sections.
16. A turntable construction including opposite span sections, a single cross girder for connecting the said span sections and having means for permitting the relative flexing of the girders of one span section independent of those of the other span section. 80
17. A turntable construction including separate flexibly connected span sections, 90 and a single cross girder connecting with both span sections.
18. A turntable construction including jointed span sections, a center and a single cross girder arranged over the center and 95 connected with the separate span sections.
19. A turntable construction including two span sections flexibly connected, the center, and a single cross girder arranged over the center and connected to both span 100 sections at their joints.
20. In a multiple span turntable, a centrally located cross girder construction, within which is located a plane of no flexure, two similar span sections connected to the cross girder construction for vertical flexing, and a rigid lateral system continuing through the span sections and cross girder construction in the plane of no flexure. 105
21. A multiple span turntable including a centrally located cross girder construction and two similar span sections having a connection with said cross girder construction to admit of vertical flexing. 110
22. In a multiple span turntable, the combination of two span sections placed in tandem, a cross girder placed between and flexibly connecting the adjacent ends of said span sections, and means for maintaining a plane of no flexure. 115
23. A multiple span turntable including separate span sections, and a centrally located cross girder having a divided web for clearing a central stationary power post. 120
24. A multiple span turntable including separate span sections, and a centrally located cross girder having a cut and spliced web for clearing a central stationary power post. 125
25. A turntable construction including op- 130

posite span sections flexibly connected with the line of no flexure located between the span flanges, and a lateral system having a rigid connection with the cross girder 5 through said line of no flexure.

26. A turntable construction including opposite flexibly connected span sections, and a cross girder located in the plane of no flexure between said span sections.

10 27. A turntable construction including opposite span sections, and a single cross girder

flexibly connecting the inner ends of said span sections and including hinging means for said sections disposed in a transverse line lying within the vertical plane of the 15 cross girder.

In testimony whereof I hereunto affix my signature in the presence of a witness.

MEIER GEO. HILPERT.
